METHOD OF FORMING A TAPERED PLATE MEMBER

Filed April 8, 1927

UNITED STATES PATENT OFFICE.

WILLIAM CLARKE S. MAYS, OF PROVIDENCE, RHODE ISLAND, ASSIGNOR TO THE MAYS MANUFACTURING CO., INC., OF PROVIDENCE, RHODE ISLAND, A CORPORATION OF RHODE ISLAND.

METHOD OF FORMING A TAPERED PLATE MEMBER.

Application filed April 8, 1927. Serial No. 182,004.

This invention relates to a method of forming a member of uneven thickness throughout its length which is plated with a precious metal; and has for its object to provide 5 a method by which the precious metal plate of the member, such as a lever for self-filling fountain pens, may be of even thickness throughout the length of the member.

With these and other objects in view, the 10 invention consists of certain novel features of construction as will be more fully described, and particularly pointed out in the appended claims.

In the accompanying drawings: 15 Figure 1 is an elevation showing the fountain pen with a lever for operating the sack within the same mounted thereon.

Figure 2 is a perspective view of the first step in the operation of forming a plated 20 lever.

Figure 3 is a perspective view of the blank.

Figure 4 is a sectional view after a portion 25 of the base metal has been removed.

Figure 5 shows the lever after being struck with a drop hammer.

Figure 6 is a perspective view of the finished lever.

Figure 7 is a central sectional view of the 30 lever formed by the old method of making the same and showing the uneven thickness of the plate stock.

It has been found in practice in the making of gold plated material which is to be 35 reduced in dimension by forming a taper or the like that the gold plate is reduced in thickness as well as the reducing in thickness of the base metal which results in the gold becoming reduced as it approaches the tapered end so as to entirely disappear from the base metal and leave the same exposed or the gold is so thinned at the tapered end as to become worn off with little use leaving the base metal exposed, to tarnish and in 40 order to avoid the thinning of the gold plate as a taper is formed on a plated lever or the like, I have cut away or removed the base metal at the tapered or thinned portion and then by striking the blank with a drop 45 hammer to elongate and form the same, the stock is bent or so formed that the gold plate is of a uniform thickness throughout the length of the lever; and the following is a detailed description of the present method

by which I form a lever having these desired 55 results:

With reference to the drawings, 10 designates the base metal to which is soldered a strip of precious metal 11, such as gold or the like which is then rolled down to suitable size effecting a corresponding or proportional reduction of the gold and the base metal. After the same has been rolled to the thickness desired a blank, as illustrated in Figure 3, is formed of the required length and from this blank there is removed as at 12 a portion of the base metal to cause the same to be tapered on the back at one end 13, as illustrated in Figure 4. With the blank thus cut away I strike the same with a drop hammer which elongates the same, as illustrated in Figure 5, and at the same time forms the base metal into the shape illustrated in Figure 5 with its back surface 14 in substantially a single plane and the 70 precious metal plate 11 being disposed in different planes being of substantially even thickness throughout the length of the member from the thick end 15 of the lever to the narrower end 13 of the same. After the lever is thus formed with the gold plate of even thickness throughout its length, it is drilled as at 16 to receive its pivotal mounting and cut away as at 17 to further adapt it for use in the connection with a fountain 75 pen 18, as illustrated in Figure 1, it being understood that the gold plate is on the outer or front surface of the lever to ornament the same and prevent it from tarnishing.

Figure 7 illustrates a lever formed by the method of drawing the plate 11 and base metal 10 without removing the base metal which results in the thinning of the plate as at 20 with an entire absence of the gold as at 19 to expose the base metal. Such a method of forming a lever with the plating of uneven thickness throughout its length is undesirable and avoided by the present method of construction.

I have provided an improved method of forming a lever for operating the sack of a fountain pen whereby the gold plate may be of even thickness throughout the length of the lever to better resist wear on the 105 tapered end and present an attractive un-tarnished appearance throughout the life of the lever.

Having thus described one illustrative embodiment of my invention and the best mode known to me for carrying out my method, I desire it to be understood that although specific terms are employed, they are used in a generic and descriptive sense and not for the purpose of limitation, the scope of the invention being defined and limited only by the terms of the appended claims.

I claim:

1. A method of forming a gold plate lever of uneven thickness throughout its length, which includes soldering the gold plate to the base metal body, rolling the plated body to the desired thickness, cutting a blank, removing a portion of the base metal, striking the blank in a drop hammer to cause the blank to become elongated and thinner in one part of its length than the other with the gold plate remaining substantially the same thickness throughout the length of the lever.

2. A method of forming a gold plate lever

tapered at one end for a self filling fountain pen, which includes cutting a blank of uniform thickness having rolled gold plate, cutting away the base metal on the back of the lever at one end of the blank, striking the blank to form the back of its base metal substantially in a single plane and the front gold plate of substantially the same thickness throughout its length with the lever substantially narrower at one end than the other.

3. A method of forming a gold plate lever of uneven thickness throughout its length, which includes cutting a blank of uniform thickness having gold plate, removing a portion of the base metal, striking the blank to elongate the same and moving the gold plate adjacent the removed portion out of the plane in which it first lies without materially changing the thickness of the gold plate throughout the length of the lever.

In testimony whereof I affix my signature.

WILLIAM CLARKE S. MAYS.
